SET-O-TYPE MANUFACTURING COMPANY, OF CLEVELAND, OHIO, A CORPORATION
OF DELAWARE

TABULATOR FOR TYPOGRAPHIC MACHINES

Application filed July 17, 1928. Serial No. 293,386.

This invention relates to new and useful improvements in tabulators for typographic machines.

It is one of the principal objects of my invention to provide a tabulator for informing the operator of the exact number of type there are in each line of the printing segment or chase plate of a typographic machine. With this information, it is possible for the

operator to properly margin each line.

It is another object of my invention to provide means, in connection with this tabulator, for keeping a perpetual inventory of the number of type used in the machine on a particular job or during a certain period.

It is still a further object of my invention to provide means for automatically returning the tabulating cylinder to zero each time the printing chase plate is indexed for the next line.

Other important and incidental objects will be brought out in the following specification and particularly set forth in the subjoined claims.

In the accompanying drawings illustrating my invention, Figure 1 is a perspective view of a typographic machine equipped with my improved tabulating means. Figure 2 is a front view of the keyboard and tabulating means. Figure 3 is an end view of the tabulator, showing the reset mechanism. Figure 4 is a view of the opposite end of the tabulating means, showing the operating solenoid. Figure 5 is a longitudinal section taken through the tabulator. Figure 6 is a cross sectional view taken on the line 6-6 of Figure 5, showing the indexing mechanism. Figure 7 is a sectional view taken on the line 7-7 of Figure 5, showing the relation of the scale and pointer to the tabulator drum. Figure 8 is a diagrammatic view of the tabulator drum, showing the indicating means. Figure 9 is a plan view of the magnetic switch for controlling the operation of the solenoid. Figure 10 is a side view thereof. And Figure 11 is a wiring diagram of the machine.

Referring to the accompanying drawings for a detailed description of my invention, the numeral 1 designates a typographic machine of the type disclosed in my United

States Letters Patent No. 1,686,031, granted October 2nd, 1928.

My improvements upon this machine lie in the tabulating mechanism carried by the keyboard 2. This tabulating mechanism is so constructed that the operator will be informed of the exact number of type there are in each line of the printing segment or chase plate of the machine.

The tabulating mechanism will now be described. Projecting upwardly above the platen 3 from the rear portion of the keyboard 2 are two side arms 4 and 5. These side arms are formed with inwardly projecting bosses 6, 6 at their middle portions. These boss portions of the side arms are formed with axial holes to receive the ends of a slidable shaft 7. (See Figures 2 and 5.)

Loosely mounted on the shaft 7, for a free movement around it, is a drum 8. This drum, which is shown diagrammatically in Figure 8, has formed on its outer periphery an indicating band or line 9 which extends from one corner of the drum to the other when the same is flattened out, as illustrated in said figure. Mounted in front of the drum 8 is an indicating scale 10, being placed in such a position that when the drum is rotated, the line 9 will come into registry with successive graduations on the scale as shown in Figure 2.

The scale 10 is secured to a horizontal, concaved supporting member 11, which is attached at its ends to the side members 4 and 5. Slidably secured to the member 11, in the manner shown in Figure 7, is a pointer 12 which as a projection 12^a that enters the U-shaped or concaved portion of the supporting member 11. As shown in said Figure 7, the pointer 12 has a U-shaped lower end, 90 which at its upper free extremity is curved for engagement with the rear surface of the concaved portion of said supporting member, whereby it may be firmly held on said supporting member without interference with its free movement along it. This pointer 12 may thus be freely adjusted on the member 11 to bring it to a predetermined graduation on the scale as shown in Figure 2. Accordingly, the pointer 12 may be set in any posi-

60

65

70

75

100

tion across the scale to show the desired limit of marginal spacing of the type. Then, when the drum has been rotated to a point where the indicating line 9 coincides with the 5 scale graduation in alignment with which the pointer is set, the operator will know that this marginal limit has been reached.

From Figure 5 it will be seen that the inner end of the drum 8 is fitted at its middle 10 portion in a groove in a collar 15 that is freely rotatable around the shaft 7. The other end 16 of the drum is secured at its middle portion to a collar 17 that is also free to rotate around the shaft 7. Secured in a 15 hole 18 in the collar 15 is a spring 19 which is coiled around the shaft 7 and secured at its inner end in a hole 20 in a block 21 firmly attached to the shaft 7 by a set screw 22. It is against the tension of this spring that the 20 drum is rotated a distance corresponding to each graduated space on the scale when a key 13 has been depressed.

The drum 8 is rotated by the following means when a key 13 is depressed. Secured 25 to the inner end of the drum is a friction disc 23 which is adapted to be engaged by friction pads 24 secured to brackets 25 attached to the outer face of a gear 27. (See Figures 5 and 6.) This gear has a hub 28 30 which is mounted on a sleeve 29 that surrounds a reduced portion of the shaft 7 between the collar 15 and a block 30 pinned to said shaft.

Secured in axial holes in the hub 28 of the 35 gear 27, are pins 31 which, when the gear is moved inwardly by the shaft 7, will engage the boss 6 on the end member 4. Thus anchored against the boss, these pins will limit the inward travel of the drum 8 when the 40 gear 27 is moved inwardly away from it.

The spring 19 is under sufficient compression to exert an outward force upon the shaft 7. Since the gear 27 is secured to the shaft between its shouldered portion and the block 45 30, the outward movement of said shaft induced by the spring will bring the friction pads 24 on the gear into firm engagement with the friction disc on the drum to rotate the latter when the gear is turned.

50 The gear 27 is rotated by the following means. Mounted on a shouldered stud 32 secured to the end member 4, is a pinion 33 which meshes with the gear 27. Also mounted on the stud 32 is a ratchet 34 formed with 55 a shoulder 35 which separates it from the pinion. (See Figures 5 and 6.)

The ratchet 34 is actuated by a pawl 36 pivotally secured by a pin 37 to the free end of a lever 38. The latter is pivotally secured by a pin 39 to the end member 4. The lever 38 terminates at its rear end in a tail 40 to which one end of a helical spring 41 is secured. The other end of this spring is secured to a pin 42 on the end member 4. This 65 spring withdraws the pawl 36 from engage-

ment with the ratchet 34 after it has been rotated the distance of one tooth. The pawl itself is held in engagement with a tooth of the ratchet 34 by a tension spring 43 in a slot 44 in the lever 38, one end of said spring being attached to the pawl and its other end to a tail piece 45 in the slot.

70 The upper portion of the lever 38 is formed with an ear 46 that is adapted to be engaged by the plunger 47 of a solenoid 48. (See Figures 4 and 6.) This solenoid is mounted in a cylindrical boss 49 that is secured to the end member 4. (See Figures 2 and 4.)

When a key 13 is depressed, the solenoid 48 is energized by means now to be described, 80 to move its plunger 47 against the ear 46 on the lever 38 to rotate the ratchet 34 one tooth. The latter, through the mechanism described, turns the drum 8 a sufficient distance to advance the indicating line 9 to the next graduation on the scale 10, thus revealing to the operator that one more type has been placed on the chase plate 50.

85 Each key 13 is in an electric circuit with a magnetic switch 51 and the solenoid 48. A feed cord 52 which is adapted to be connected to an electric socket not shown, leads to the keyboard 2. Referring to the wiring diagram shown in Figure 11, one feed wire 53 of the cord 52 leads to a terminal 54 on the magnetic switch 51. The other feed wire 55 of said cord supplies current to the type ejector solenoids 56 through branch wires 57. Each solenoid 56 is placed in circuit with a contact leaf directly below the stem 59 of a key 13.

90 The contact leaf 58 belonging to a key 13 is adapted to be pressed into engagement by it with a contact 60 from which a wire 61 leads to a terminal 62 on the magnetic switch 51. This terminal 62 is connected by a wire 63 to a magnetic coil 64. (See Figures 9 and 11.) The coil 64 is connected to the terminal 54 of the magnetic switch 51 by a wire 65. By a branch wire 66 the solenoid 48 is connected to the feed wire 55, and also to a terminal 67 on the magnetic switch 51 by a wire 68. A branch wire 69 leads from the feed wire 53 to a terminal 70 on the switch 51.

95 On the magnetic switch 51 there is a contact leaf 71 which is secured at one end to the terminal block 70 and which is free at its other end to engage the terminal block 67. It 100 will now be seen that when a key 13 is depressed, the contact leaf 58 will engage the contact 60 to close an electric circuit through the magnetic switch 51, whereupon its contact leaf 71 will be drawn by the magnetic coil 64 against the terminal block 67 to close 105 a circuit through the tabulator solenoid 48. Being thus energized, said solenoid will move the plunger 47 outwardly to turn the ratchet 34 one tooth, thereby rotating the drum 8 a sufficient distance to move the indicating 110

line 9 from one graduation on the scale 10 to the next graduation thereon.

When the drum 8 has been rotated by the keys 13 as before described, to bring the indicating line 9 to the scale graduation directly in line with the pointer 12, the operator will immediately know that the predetermined marginal limit in the chase plate 50 has been reached, which means that no more type or quads should be placed in that line. At this point the drum 8 will be rotated in a reverse direction by the following means to return the line 9 to its zero position with respect to the scale 10.

Referring to Figure 5, the knob 72 which turns the platen roll 73 is free to slide inwardly on the platen roll shaft 74. In the path of inward movement of the knob 72 is the lower fork end of a release lever 75 which 20 straddles the shaft 74. This lever 75 is pivotally secured at its upper end by a pin 76 to an overhanging ear 77 on the end member 5. Projecting from the lower portion of this end member is a guide 78 for said lever.

Formed on the upper middle part of the lever 75 is a protuberance 79 which is adapted to engage the end of the shaft 7. (See Figure 5.) Now, when it is desired to return the line 9 to its zero position, the knob 72 is 30 pressed inwardly, whereupon it will engage and force inwardly the free end of the lever 75. Through its engagement with the shaft 7, the lever 75 will force it inwardly.

Since the rear end of the shaft 7 is provided 35 with a shoulder 80 against which the sleeve 29 abuts, the gear 27 will be forced inwardly by the shaft 7 when the latter is engaged by the lever 75. And when this gear is thus shifted inwardly, it will move away from the drum 8 because the inward travel of the latter will be limited by the stop pins 31, 31 as before described. The drum 8 being thus released from frictional engagement with the gear 27, will be free to be rotated in a reverse 40 direction about the shaft 7 by the spring 19, which had been placed under torsional tension 45 when the drum was rotated by the pawl 38.

For the purpose of adjusting the zero position of the indicating line 9 of the drum 8, the following adjustable stop means are provided. Referring to Figures 3 and 5, there is secured to the front end 16 of the drum, beyond its center, a stop disc 81 which is adapted 50 to engage a right angled projection 82 on a stop arm 83 which is pivotally secured by a pin 84 to the end member 5. The latter is provided with an arcuate slot 85 through which the projection 82 is free to move. The stop arm 83 itself is provided with a clearance slot 86 for the shaft 7.

For the purpose of holding the stop arm 83 in an adjusted position to halt the reverse rotation of the drum 8 at the proper zero position for the indicating line 9 with respect

to the scale 10, said arm is formed with an arcuate slot 87 through which a screw 88 is inserted into the end member 5. (See Figures 3 and 5).

For the purpose of preventing the shaft 7 from turning when the drum 8 is rotated, there is secured to the front end of the shaft a pin 89 which enters a deep recess 90 in the boss 6 on the end member 5. (See Figure 5.)

For the purpose of counting the number of type and quads used in the machine on a particular job, or during a certain period, I provide a counter 91 of the conventional Veeder type. This counter is mounted in the upper frame of the tabulator in a position to bring its operating pinion 92 into engagement with the gear 27, whereby it may be operated by the latter to record the number of type and quads that have been placed in the printing chase of the machine for a particular job or over a definite period of time. (See Figures 4 and 6).

In the drawings I have shown the drum 8 housed in a cylindrical casing 93 which is open at its ends for support by the end members 4 and 5. Through a horizontal opening 94 in the front portion of the casing, that part of the indicating line 9 which is just above the scale 10 is at all times visible to the operator.

I do not wish to be limited to the details of construction and arrangement herein shown and described, and any changes or modifications may be made therein within the scope of the subjoined claims.

Having described my invention, I claim:

1. A device of the type described, comprising a group of type-ejector keys, a scale associated therewith, a rotatable drum, a band on the periphery of said drum adapted to traverse the scale when the drum is rotated, and means for operation by anyone of said keys to rotate the drum to advance the band from one graduation to the next succeeding graduation on the scale.

2. A device of the type described, comprising a group of type-ejector keys, a scale associated therewith, a rotatable drum, a band on the periphery of said drum adapted to traverse the scale when the drum is rotated, and electrical means for operation by any one of said keys to rotate the drum to advance the band from one graduation to the next succeeding graduation on the scale.

3. A device of the type described, comprising a group of type-ejector keys, a scale associated therewith, a rotatable drum, a band on the periphery of said drum adapted to traverse the scale when the drum is rotated, a ratchet for rotating said drum, a solenoid for turning said ratchet, and electrical means operated by anyone of said keys to actuate the solenoid to rotate the drum to advance the band from one graduation to the next succeeding graduation on the scale.

4. A device of the type described, comprising a group of type-ejector keys, a scale associated therewith, a rotatable drum, a band on the periphery of the drum adapted to traverse the scale when the drum is rotated, a padded gear slideable into frictional engagement with one end face of the drum to rotate the same a distance sufficient to move the band through one space on the scale when one of said keys is depressed, and means for withdrawing said padded gear from said drum to permit it to be returned to its zero position.

5. A device of the type described, comprising a group of type-ejector keys, a scale associated therewith, a rotatable drum, a band on the periphery of the drum adapted to traverse the scale when the drum is rotated, a slideable shaft on which the drum is mounted, a gear free to be rotated around said shaft and in engagement with one end face of the drum, and means for rotating said gear a sufficient distance to move the band on the drum through one space on the scale when a key is depressed, said shaft being free to be forced inwardly to move the gear away from the drum when it is desired to return the latter to its zero position.

6. A device of the type described, comprising a group of type-ejector keys, a scale associated therewith, a slideable shaft, a drum rotatably mounted on said shaft, a gear loosely mounted on said shaft and adapted to be shifted longitudinally with it, a spring coiled around the shaft and secured at one end to the latter and at its other end to the drum to draw the gear into frictional engagement with one face of said drum, means for rotating said gear a sufficient distance to move the band on the drum through one space on the scale when a key is depressed, and means for holding the drum against inward movement when the shaft and gear are forced inwardly whereby the spring will rotate the drum to its zero position.

7. A device of the type described comprising a slideable shaft, an indicating drum rotatably mounted on said shaft and adapted to be shifted longitudinally with it, a driving gear having a hub rotatably mounted on said shaft, for frictional engagement with one end face of said drum, a stop member adjacent said gear, the hub of the latter being formed with axial holes, and stop pins loosely projecting through said holes for engagement with the drum and stop member to hold the drum against inward movement when the gear is moved inwardly by the shaft.

8. A device of the type described, comprising a slideable shaft, an indicating drum rotatably mounted on said shaft, a driving gear rotatably mounted on the shaft for frictional engagement with one end face of the drum to rotate it, means for holding the drum against inward movement, means for fixing the gear on the shaft for an inward movement

by the latter without disturbing its freedom of rotation about said shaft, and a lever adapted to engage the front end of the shaft to move it inwardly and thereby to withdraw the gear from frictional engagement with the drum for the purpose specified.

9. In a device of the type described, a pair of supporting members, a shaft slidably journaled therein, a drum rotatable around the shaft, a stop arm pivotally secured at one end to one of said supporting members, said supporting member formed with an arcuate slot, a stop projection on said arm extending through said slot, and a fixed element on the adjacent face of the drum for engagement with the projection on the stop arm to halt the rotation of the drum at a predetermined point.

10. In a device of the type described, a pair of supporting members, a shaft slidably journaled therein, a drum rotatable around the shaft, an adjustable stop arm pivotally secured at one end to one of said supporting members, said supporting member formed with an arcuate slot, a stop projection on said arm extending through said slot, a fixed element on the adjacent face of the drum for engagement with the projection on the stop arm, said arm formed with an arcuate slot, and a screw adapted to be inserted through said slot into the adjacent end member to hold the arm in an adjusted position for the purpose specified.

11. In a device of the type described, a group of type-ejector keys, a scale associated therewith, a rotatable drum, indicating means on the periphery of the drum adapted to be moved by it one graduated space on the scale when a key is depressed, and a counter for recording the number of graduated spaces on the scale traversed by said indicating means.

12. In a device of the type described, a group of type-ejector keys, a scale associated therewith, a rotatable drum, indicating means on the periphery of the drum adapted to be moved by it one graduated space when a key is depressed, a gear for rotating said drum, and a counter driven by said gear for recording the number of graduated spaces on the scale traversed by the indicating means.

13. A device of the type described, comprising a group of type-ejector keys, a scale associated therewith, a rotatable indicator, means on the latter adapted to traverse the scale when the indicator is rotated, electrical means for rotating said indicator, an electric switch, and an electric circuit including said switch and electrical means, said switch adapted to be closed by a key, when depressed, to close the circuit including the electrical operating means for the purpose specified.

14. A device of the type described, comprising a shaft, a drum mounted on said shaft, a gear for rotating said drum, a pinion in mesh with said gear, a ratchet operatively

connected to said pinion, a lever, a pawl carried by said lever for engagement with said ratchet, a solenoid, a plunger in said solenoid for engagement with said lever, an electric circuit including said solenoid, a switch for closing said circuit, and a typewriter key for operating said switch.

In testimony whereof I have hereunto set my hand this 14th day of July, 1928.

FRANK H. POEPPELMEIER.
